UNITED STATES PATENT OFFICE.

WILLIAM S. TOTHILL, OF CHICAGO, ILLINOIS.

MERRY-GO-ROUND.

1,130,217.

Specification of Letters Patent.

Patented Mar. 2, 1915.

Application filed March 5, 1914. Serial No. 322,602.

To all whom it may concern:

Be it known that I, WILLIAM S. TOTHILL, a citizen of the United States, residing at Chicago, in the county of Cook, in the State of Illinois, have invented certain new and useful Improvements in Merry-Go-Rounds, of which the following is a specification, reference being had to the accompanying drawings.

10 This invention relates to merry-go-rounds and particularly to that type of merry-go-rounds shown in the United States patent granted to me on September 16, 1913, No. 1,073,449.

15 It is one of the objects of my invention to provide new and improved means for securing the inner ends of the radially-positioned beams of the platform of the device whereby the beams may be held securely in place 20 and whereby they may be tightened from time to time as the necessity may arise.

It is another object of my invention to provide new and improved means for holding the said radially-positioned beams of 25 the platform in proper position relative to each other whereby the platform is prevented from sagging down at its outer edge.

It is another object of my invention to provide new and improved means for securing 30 the platform firmly in position relative to the supporting member whereby the platform is held constantly in the proper plane and is prevented from rocking relative to the support.

35 It is another object of my invention to provide a new and improved means for rotating the platform.

It is another object of my invention to provide a new and improved spring support 40 for the horses or other animals provided on the platform.

It is another object of my invention to improve devices of this type in sundry details hereinafter pointed out.

45 The preferred means by which I have accomplished these objects are illustrated in the accompanying drawings and are herein-after specifically described.

That which I believe to be new is set forth 50 in the claims.

In the drawings,—Figure 1 is a top view of my improved merry-go-round, broken away at one side and having the platform broken away at the other side to better show 55 the means for holding the platform beams

in proper position relative to the standard; Fig. 2 is a central vertical section through the device taken on line 2—2 of Fig. 1; Fig. 3 is a side view of the cap which encircles the standard immediately above the bearing of the platform; Fig. 4 is a view illustrating the construction of the spring by which the horses are supported upon the platform; Fig. 5 is a detail of the spider in which the inner ends of the platform beams are mounted; and Fig. 6 is a detail of one of the devices for tightening the rods, which extend through the platform beams for holding said beams in proper position relative to the standard.

Referring to the several figures of the drawings in which corresponding parts are indicated by the same reference characters,— 70 10 indicates a base of any suitable form, having mounted thereon a plate 11 from which rises a standard 12. Surrounding the standard 12 and spaced away therefrom is a bearing-ring in the form of a spider provided with a plurality of radially-disposed sockets for the platform beams 14, 80 the inner ends of which beams abut against the standard 12. As best shown in Fig. 2 each of the beams 14 is provided with a plate 15 underneath its inner end, 85 against which plates the set-screws 16 carried by the spider 13 are adapted to bear. As will be readily understood, the outer ends of the beams 14 are adapted to be raised relative to the spider 13 by means of the set-screws 16, whereby the beams 14 can be 90 adjusted relative to each other to keep the platform in proper alignment.

17—18 indicate steel rings mounted upon the plate 11 and the spider 13, respectively, between which steel rings are mounted a 95 plurality of balls 19 held in proper relation to each other by a spacing device 20.

21 indicates a cap mounted upon the standard 12, said cap comprising a collar 22 secured in position by a pin 23 passing through suitable holes through the collar and through the standard 12 and by set-screws 24 carried by said collar at opposite sides bearing on said standard. Said cap also comprises a pressure-plate 25 adjustably connected to the cap by bolts 26.

27 indicates set-screws mounted in a flange of the collar 22 bearing against the pressure-plate 25. As will be readily understood, by loosening the nuts on the bolts 26 and 110

then tightening up the bolts 27 the pressure-plate 25 of the cap can be spaced away from the collar 22 as desired.

As best shown in Fig. 2, 28—29 indicate bearing rings carried by the cap 21 and the spider 13, respectively, between which bearing rings are interposed a series of balls 30 held in proper relation to each other by a spacing device 31.

10 With the frame comprising the spider 13 and the beams 14 in position upon the standard 12 between the two sets of anti-friction devices, by a proper adjustment of the set-screws 27 the play of the frame or platform between the cap 21 and the plate 11 can be limited as desired, preventing the frame from canting relative to the standard, thus maintaining the parts in proper working position.

20 The means for adjusting the beams 14 relative to each other for tightening the frame about the standard when it becomes loose through any means consists of an adjustable rod 32 formed in sections joined together by couplings 33. As will be understood from an inspection of Fig. 6 the coupling 33 comprises two sleeves joined together along their adjacent edges, the sections of the rod 32 being screw-threaded at their ends whereby the length of the rod 32 may be varied as desired. As shown in Figs. 1 and 2 the rod 32 passes through suitable holes through the beams 14 at a suitable distance from the standard 12.

35 When the ends of the beams 14 become worn or the platform otherwise becomes loosened in its joints, or relative to the standard 12, the rod 32 may be tightened by turning the nuts on the sections of the rod. It has been found that in this manner the beams 14 can be moved a short distance inward when required, tightening up the platform as a whole very effectually.

34—35 indicate seats made in simulation of chariots secured upon the platform of the merry-go-round, and 36 indicates a hobby-horse secured by a suitable spring device upon said platform. As best shown in Fig. 4, the spring support for the hobby-horse comprises a curved flat spring 37 secured at one end to the horse and at the other end to the base or platform, and a second curved flat spring 38 positioned inside the curve of the spring 37, the spring 38 being also secured to the base or platform at its lower end. In the construction shown the spring 38 is secured at its upper end by means of a clip 39 to the spring 37.

40 indicates a cross-head fixed upon the upper end of the standard 12 provided with handles 41 rising from its ends. As will be readily understood a boy standing upon the platform of the device can grasp the handles 41 of the cross-head 40 and by an action as if to turn the cross-head 40 can

cause the platform itself to revolve. In this action, as will be readily understood, there is brought into play a great variety of muscles through practically the entire body, the device as a whole being thus constituted a high class exerciser and developer as well as an amusement device.

What I claim as my invention and desire to secure by Letters Patent, is—

1. The combination of a standard, a frame revolvably mounted on said standard, a supporting plate having a rigid connection with said standard below said frame, anti-friction devices interposed between said plate and said frame, a collar fixedly secured to said standard and held in non-adjustable position above said frame, anti-friction devices interposed between said collar and said frame, and adjustable means for taking up any play of the anti-friction devices and said frame between said supporting plate and said collar.

2. The combination of a standard, a frame revolvably mounted on said standard, a supporting plate having a rigid connection with said standard below said frame, anti-friction devices interposed between said plate and said frame, a collar fixedly secured to said standard and held in permanent fixed position above said frame, anti-friction devices interposed between said collar and said frame, and adjustable means carried by the collar for taking up any play of the anti-friction devices and said frame between said supporting plate and said collar.

3. The combination of a standard, a frame revolvably mounted on said standard, a supporting plate having a rigid connection with said standard below said frame, anti-friction devices interposed between said plate and said frame, a collar fixedly secured to said standard above said frame, a pressure-plate loosely mounted on said standard below said collar, anti-friction devices interposed between said pressure-plate and said frame, and set-screws adapted to space said pressure-plate away from said collar for taking up any play of the anti-friction devices and said frame between said supporting plate and said collar.

4. The combination of a standard, a frame revolvably mounted on said standard, a supporting plate having a rigid connection with said standard below said frame, anti-friction devices interposed between said plate and said frame,—a cap comprising a collar fixedly secured to said standard above said frame, a pressure-plate adjustably secured to said collar, and set-screws carried by said collar adapted to space said pressure-plate therefrom,—and anti-friction devices interposed between said pressure-plate and said frame.

5. In a merry-go-round, the combination

- of a base, a standard fixedly secured to said base and rising therefrom, a platform revolvably mounted on said standard, anti-friction devices interposed between said base and said platform, a collar about said standard above said platform, a pin extending through said collar and through said standard for holding the collar non-adjustably in position, anti-friction devices interposed between said collar and said platform, and adjustable means for taking up any play of the anti-friction devices and said platform between said base and said collar. 5
- 10 6. The combination of a support, a bearing-ring revolvably mounted on said support, a plurality of converging beams mounted on said bearing-ring, and adjustable means having bearings on both said bearing-ring and said beams for adjusting the beams to proper alinement when such beams sag in use at their outer ends. 15
- 20 7. The combination of a support, a bearing-ring revolvably mounted on said support, a plurality of converging beams mounted on said bearing-ring, and set screws having bearings on both said bearing-ring and said beams for adjusting the beams to proper alinement when such beams sag in use at their outer ends. 25
- 25 8. The combination of a support, a frame revolvably mounted on said support,—comprising a spider, and a plurality of beams having their inner ends mounted in suitable sockets in said spider,—and set-screws having bearings on both said spider and said beams for adjusting the beams to proper alinement when such beams sag in use at their outer ends. 30
- 30 9. The combination of a support, a frame revolvably mounted on said support,—com- 35
- prising a spider, and a plurality of beams having their inner ends mounted in suitable sockets in said spider,—and set-screws mounted in said spider farther outward along said beams than the outer ends of said sockets, said set-screws being adapted to be adjusted vertically against the under faces of said beams for raising the outer ends of the beams. 45
10. The combination of a standard, a platform revolvably mounted on said standard,—comprising a spider having a plurality of radial sockets, a plurality of beams having their inner ends mounted in said sockets, and a plurality of plates mounted on the under faces of said beams,—and set-screws mounted in said spider below said beams farther outward therealong than the outer ends of said sockets, said set-screws being adapted to be adjusted vertically against the under faces of said plates for raising the outer ends of said beams. 50
11. In a merry-go-round, the combination of a revolvably mounted platform, a stationary standard extending upward through said platform at approximately the axis of rotation thereof, a cross-head fixedly mounted on said standard above said platform, and handles rising from said cross-head. 55
12. In a merry-go-round, the combination of a standard, a platform revolvably mounted thereon, a cross-head fixedly mounted on said standard at its upper end above said platform, and handles mounted on said cross-head and rising therefrom one at each end. 60
